UNITED STATES PATENT OFFICE.

ELMER P. MCCLURE, OF WESTERN SPRINGS, ILLINOIS.

POLISHING MACHINE.

1,425,666.

Specification of Letters Patent. Patented Aug. 15, 1922.

Application filed October 27, 1919. Serial No. 333,573.

To all whom it may concern:

Be it known that I, ELMER P. MCCLURE, a citizen of the United States, residing at Western Springs, in the county of Cook and State of Illinois, have invented certain new and useful Improvements in Polishing Machines, of which the following is a specification.

My invention relates to a machine for 10 buffing metal articles of cylindrical or approximately cylindrical shape and symmetrical about a radial line, such as pots, kettles, pans, and other cooking utensils usually made of sheet metal, and has for its 15 object the provision of practical and efficient mechanism, by means of which such articles may be polished automatically, the attention of an operator being required only to insert the article in position to be operated upon, and remove it when the buffing 20 is completed. With this general object in view, I have designed and invented the novel buffing machine hereinafter described and illustrated in the drawings forming a 25 part of this application, and my invention consists in the new organization and arrangements of the parts of the machine, various new combinations and sub-combinations 30 of cooperating members, and in subordinate details of construction in certain parts and portions of the mechanism which I have devised in carrying out my invention and embodying it in a practical form. In the appended claims I have recited the 35 essential element of my invention, it being understood, however, that certain groups or subcombinations of elements may be employed in machines differing in other respects from the particular machine illustrated in the drawings and hereinafter described, and that my invention is not to be limited to the precise structure illustrated in the drawings and hereinafter described further than is essential to the subject matter 45 of certain of the claims; and that variations in the form and construction of different parts and changes by the substitution of equivalent elements or combinations of elements may be made without departing 50 from the spirit and substance of my invention.

Of the drawings Figure 1 is an elevation of the right hand side of the machine (the base or pedestal being broken away); Fig. 55 2 is an elevation of the left hand end; Fig.

3 is a front view of the machine with the swinging frame which supports the article to be operated and the mechanism for rotating it removed; Fig. 4 is a front view of such work-supporting frame, detached from the machine; Fig. 5 is a plan view; and Fig. 6 is a detail sectional view showing the manner in which the worm wheel by which the work-carrying shaft is rotated is connected with such shaft. 60

The same reference characters indicate the same parts in all the figures of the drawing.

Describing now the particular embodiment of my invention shown in the drawings, my novel buffing machine comprises a stationary frame in which are adjustably mounted a pair of power driven shafts or spindles equipped with polishing wheels, and a work-holding member mounted upon 70 a shaft or spindle which is given both longitudinal and rotary movement and is mounted in a movable frame through which the articles carried by the work-holder may be shifted into and out of cooperative relation with the polishing wheels. 75

The frame of the machine may conveniently be formed, as shown, of two cast metal members, a lower part or base 1, the upper part only of which is shown, and a 85 hollow upper casting 2 secured to the base. The front wall of the upper frame member extends laterally to form vertical flanges 3—3, and these flanges and the front wall are machined to provide a true surface 90 adapted to fit the contiguous machined faces of a vertically adjustable bearing plate 4 flanged at its opposite sides and of guide blocks 5—5 bolted to the flanges of the plate and engaging the rear faces of the 95 flanges 3—3.

The plate 4 may be slidably adjusted up or down by means of an adjusting screw 6 mounted in a threaded bracket 7 projecting from the front of the base member 1 and 100 having at its upper end swiveled connection with a lug 8 projecting forwardly from the front face of the plate at the center of its lower edge. The plate is formed with a pair of vertical slots 9—9 adapted to receive the reduced threaded ends of clamping screws 10—10 engaging threaded seats in the frame member 2. These screws are intended to be loosened when the adjustment of the plate 4 is to be changed, and 105 110

tightened when the adjustment is made to clamp the plate securely to the frame member.

The bearing plate 4 is formed with journal bearings 11 in which is mounted a spindle 12, to which is secured at the left hand side of the machine, a pulley 13, and also, at the right hand side, a set of spaced buffering disks 14, each constructed in the usual manner of a number of plies of fibrous or other suitable material secured together. In the present instance these disks are separated from each other by the laterally extending portion of the hubs 15 of the hubs to which the disks are secured, and the hubs and connected disks are removable and interchangeable in order that disks of different diameters may be assembled to conform to the peripheral surface of an article which is not cylindrical, but of varying diameter.

Upon the top of the frame member 2 is arranged a bearing plate 16, similar in construction and arrangement to the plate 4, but mounted to be slidably adjusted fore and aft to the machine in a horizontal plane by means of an adjusting screw 17, and secured in adjusted position by clamping screws 18, similar in construction to the adjusting screw 6 and clamping screws 10 before mentioned. Journaled in bearings carried by this top bearing plate 16 is a spindle 19 to which is secured a pulley 20 and a set of buffering disks 21 which are similar to the disks 14 but are staggered or offset with respect to them, as shown in Figs. 3 and 5.

The two sets of buffering wheels are arranged to be rotated by means of a belt 22 engaging a suitable driving pulley (not shown) which engages the pulleys 13 and 20 and an intermediate adjustably mounted idler pulley 23. As shown—see Figs. 2 and 5—, this idler take-up pulley is rotatably mounted upon a stub shaft 24 secured to a plate 25 which is slidably mounted in a guideway between opposite plates 26 by means of an adjusting screw 27 rotatably engaging an orificed lug 28 in the plate 25 and a threaded seat in a lug 29 formed on the adjacent sidewall of the frame member 2. As will be readily understood the idler pulley 23 may thus be adjusted to give the belt the proper tension, in any positions of adjustment of the pulleys 13 and 20.

The mechanism by means of which the article to be polished is presented to the buffering wheels will now be described. As shown in Figs. 1, 2 and 3, the base member 1 is formed with hinge members 30 bored to receive a pintle 31 upon which is pivotally mounted hinge members 32 formed at the bottom of a swinging frame 33 (see Fig. 4), consisting of opposite rearwardly curved side members 34—34^a which at their top and rear are connected to vertical end portions 35—35^b, respectively, and of top and bottom

cross members, marked 36 and 36^a, respectively, flanged as shown to give maximum strength. The swinging frame is swung backwards and forwards upon its pivot to and from working position by means of a hand wheel 37 and connected screw shaft 38 having swiveled connection at its rear end with a block 39 pivoted to the frame member 2 and engaging an internally-threaded block 40 pivoted upon the side number 34 of the frame.

At the left hand side of the machine and at the top of the side member 34^a the frame is formed with a bracket 41 upon which is mounted a small electric motor 42, which may be of any suitable construction provided with a starting switch, and having the proper capacity to drive the work holder and perform the work for which the machine is designed. The motor shaft is connected with a worm 43 which drives a worm gear 44 mounted upon a hollow stub shaft 45 rotatably mounted in a hub bearing 46 formed in the frame member 34^a at the rear side of the bracket 41, nuts 47 and 48 serving to hold the shaft in its bearing. The work-holding shaft 49 (which, as later will be explained, has both an axial and a rotary movement) makes splined engagement with the bore of the hollow stub shaft 45 of the worm-wheel—see Fig. 6,—and also rotatably and slidably engages a hub bearing 49^a formed at the front end of the curved portion of the side member 34 of the frame.

Slidably mounted in bearings 50 and 50^a at the top of the vertical end portions 35 and 35^b respectively of the side members of the swinging frame is a shaft 51 extending parallel with the work-holding shaft 49. Secured to shaft 51 are two collars marked 52 and 53 respectively, and intermediate the collars is arranged a cross bar 54 which at its top is transversely bored to engage said shaft and at its bottom is formed with another transverse bore to engage the shaft 49, and also a double pinion having two gears 55 and 56 secured to a single hub. The work-holding shaft also has secured to it two collars 57 and 58, the collar 57 abutting against the lower end of the cross-bar 54, and the collar 58 abutting against a circular cam 59 which is integral with or secured to a gear 60 rotatably mounted on the shaft 49 and meshing with the gear 56 of the double pinion before mentioned. The cam 59 is arranged to cooperate with a cam roller 61 pivotally mounted upon a lug 62 projecting laterally from the side member 34 of the swinging frame. Confined between the cross bar 54 and the gear wheel 60 is a pinion 63 meshing with the gear 55 of the double pinion and having splined connection with the shaft 49. It is manifest that through rotation of the motor the worm gear wheel 44 will be rotated, and through

the splined connection of such wheel with the shaft 49 and the splined connection of such shaft with the pinion 63 the latter will be rotated and transmit rotary motion to the cam 59 through the double pinion 55-56 and the pinion 60. Since the collars 57 and 58 secured to the shaft 49 confine the cam 59 and cross-bar 54 and the pinions lying between them, and the collars 52 and 53 confine the cross-bar and double pinion, the rotation of the cam compels longitudinal movement of the shafts 49 and 51 as a unit. To the outer end of the shaft 51 is secured an arm 64 which axially of the work-holding shaft is bored to receive a bushing 65 threaded internally to engage a clamping screw 66 operated through a hand wheel 67. This clamping screw is bored to receive the stub shaft 68 of a relatively movable clamping member or foot stock 69 which is adapted to cooperate with a relatively fixed clamping head or head stock 70 secured to the end of the work-holding shaft to clamp between them the bottom of a pan, kettle, or other article to be polished by the buffing disks. A supplementary supporting and centering member in the form of a disk 72 is provided, adapted to be set so as to engage the open or outer end of such article as a coffee pot, or cup, and support it during the polishing operation. Between the end of the stub-shaft 68 and the end of the socket in which such shaft is rotatably mounted is interposed a thrust bearing 71 to take up the stress of the clamping screw and minimize friction.

The relationship of the gear wheels 63, 55, 56 and 60 is such that a revolution of the work-holding shaft will not be an exact multiple of a revolution of the gear wheel 60 and cam 59, so that each traverse of work holding shaft will begin with the article occupying an angular relation with respect to the position occupied at the beginning of the preceding traverse, in order to avoid having the buffing disks follow the same spiral path at each reciprocation of the article axially. For instance, the gear wheel 63 may have forty-eight teeth, the gear wheel 55 seventy-six, the gear wheel 56 forty-eight, and the gear wheel 60 seventy-six teeth, in which case the beginning of each reciprocation of the cam 59 and connected parts will occur $144/361$ of a revolution of the shaft 40 and article rotated thereby away from the position occupied by the shaft at the beginning of the previous traverse.

It will be understood that in the practical use of my machine, a considerable number of similar articles in one lot will usually be polished successively, and the machine is set to the particular article by securing to the shafts 12 and 19 buffing disks (identified on the drawings by the number 14 and 21, re-

spectively) of appropriate number and diameter and spacing, and making such adjustments of the bearing plates 4 and 16, and the idler pulley 23 as may be needed to cause the buffing while to properly engage the outer surface of the article when clamped axially between the clamping heads 69 and 70. If the article is cylindrical, as shown, the buffing disks will all be of the same diameter, but if the exterior is conical or curved, or more or less irregular outline in diametrical section, the disks will be of such diameter and so spaced and arranged as to conform to the general contour of the article. The yielding character and quality of the buffing disks is such that during the longitudinal reciprocation of the article with the work-holding shaft the disks will follow the surface of the article and conform to minor irregularities or variations in its shape, and will effectively polish every part thereof exposed to the disks. The required adjustments of the various members having once been made, the swinging frame 33 may be shifted to and from working position by means of the hand wheel 37 and screw shaft 38 to permit successive articles to be secured to the work-holding shaft, brought to working position, and then after the polishing operation has taken place, shifted to position of non-engagement to permit the next article to be secured in place. The polishing disks are preferably continuously driven, but the motor is either provided with a convenient switch by means of which it may be stopped between polishing operations, or if designed to run continuously a clutch is provided for connecting and disconnecting the motor with the work-holding shaft.

It is obvious that by suitable changes in the polishing or abrading members my invention may be employed for grinding cylindrical or approximately cylindrical articles of metal, wood, or other material, and that in some cases it may be desirable to use but one series of abrading members, or it may be unnecessary to cause the work-holding shaft to reciprocate longitudinally. I therefore do not limit my claims beyond the elements particularly recited to the entire and specific machine described.

I claim:

1. In a machine for polishing articles symmetrical about a radial line, a work-holding member arranged to engage an article and rotate it, a plurality of rotatable spindles parallel with the axis of rotation of the article and in different radial planes, said spindles being each equipped with polishing disks and the disks of the different sets being staggered with respect to each other, and means for automatically reciprocating said work-holding means axially.
2. In a machine for polishing articles

symmetrical about an axial line a shaft equipped with a work-holding member arranged to engage and rotate the article to be polished, a horizontally adjustable bearing plate and a spindle equipped with polishing disks journaled in said plate, a vertically adjustable bearing plate and a spindle equipped with polishing disks journaled in said last mentioned plate; said spindles being arranged parallel with said shaft and adjustable radially thereof.

3. In a machine for polishing articles symmetrical about an axial line, a rotatable shaft mounted to swing transversely of its axis through parallel positions into and out of working position, said shaft being equipped with work holding means arranged to engage and rotate the article to be polished, a plurality of rotatable spindles parallel with and arranged angularly about the axis of said rotatable shaft when in its working position, said spindles being equipped with polishing members having their peripheries arranged to simultaneously contact said article, and means for swinging said shaft transversely.

4. A machine according to claim 3 in which the rotatable shaft is journaled in a pivoted frame.

5. A machine according to claim 3 in which the rotatable shaft is journaled in a pivoted frame and a motor arranged to rotate said shaft is mounted on said frame.

6. A machine according to claim 3 in which the said shaft is slidably and rotatably mounted in a reciprocating frame.

7. A machine according to claim 3 in which said shaft is slidably and rotatably mounted in a reciprocating frame and a motor arranged to rotate and reciprocate said shaft is mounted on said frame.

8. A machine according to claim 2 in which said spindles are equipped with pulleys and driven by a belt and a take-up idler pulley is adjustably mounted to engage a loop of said belt intermediate said first-mentioned pulleys.

9. In a machine of the character described, a driving pinion having a tubular hub journaled in the machine frame, work-holding means including a shaft mounted to slide in said tubular hub and having splined connections therewith, said shaft being equipped with a work-holding member, a circular cam rotatably and non-slidably mounted on said shaft, reducing gearing including a pinion non-rotatably secured to said shaft and having geared connection with said circular cam, and a stationary cam member cooperating with said circular cam.

10. In a machine of the character described, work-holding mechanism including a shaft mounted to rotate and slide longitudinally and equipped with a work-holding member, driving means having splined con-

nection with said shaft, a second shaft slidably mounted parallel with said first-mentioned shaft, reducing gearing including a pinion non-rotatably secured to said first-mentioned shaft and pinions rotatably mounted on said second mentioned shaft and a pinion rotatably mounted on said first-mentioned shaft, a circular cam secured to said last-mentioned pinion, a stationary cam member cooperating with said circular cam, and means for preventing relative longitudinal movement of said shafts.

11. In a machine of the character described, work-holding mechanism according to claim 10 in which said circular cam is formed upon a hub integral with the pinion rotatably mounted on said first-mentioned shaft.

12. In a machine of the character described, work-holding mechanism according to claim 10 in which the means for preventing relative longitudinal movement of the shafts comprise a cross-bar rotatably engaging the first-mentioned shaft, a pair of collars secured to said first mentioned shaft on confining the said cross-arm and the pinions and cam mounted on such shaft, and a second pair of collars secured to said second-mentioned shaft and confining the pinions mounted on such shaft.

13. In a machine of the character described, work-holding mechanism according to claim 10 in which the pinions on said second-mentioned shaft are mounted on a single hub rotatably engaging such shaft and mesh respectively with the pinion non-rotatably mounted on said first mentioned shaft and the pinion rotatably mounted on such shaft.

14. In a machine of the character described, work-holding mechanism according to claim 10 in which the gearing ratio effects angular displacement of the work-holding member at the beginning of each longitudinal traverse with respect to the last previous position at such point.

15. In a machine of the character described, work-holding mechanism including a shaft mounted to rotate and slide longitudinally and equipped with a work-holding member, driving means having splined connection with said shaft, a second shaft slidably mounted parallel with said first-mentioned shaft, a train of gearing on said first-mentioned and second-mentioned shafts for reciprocating said first-mentioned shaft longitudinally, means for preventing relative longitudinal movement of said shafts, a clamping head fixed to the outer head of said first-mentioned shaft, an arm fixed to the outer end of said second-mentioned shaft, and a freely rotatable clamping member mounted in said arm.

16. In a machine of the character described, work-holding mechanism according to claim 10 in which the work-holding mechanism includes a shaft mounted to rotate and slide longitudinally, a work-holding member having splined connection with said shaft, a second shaft slidably mounted parallel with said first-mentioned shaft, a train of gearing on said first-mentioned and second-mentioned shafts for reciprocating said first-mentioned shaft longitudinally, means for preventing relative longitudinal movement of said shafts, a clamping head fixed to the outer head of said first-mentioned shaft, an arm fixed to the outer end of said second-mentioned shaft, and a freely rotatable clamping member mounted in said arm.

to claim 15 in which the clamping head on said first mentioned shaft is fixed to such shaft and the clamping head mounted in said arm is movable in respect to such arm.

5 17. In a machine of the character described, work-holding mechanism according to claim 15 in which the clamping head on said first mentioned shaft is relatively fixed and the clamping head mounted in said arm 10 is formed with a stem rotatably engaging a screw shaft making threaded engagement with such arm.

18. In a machine of the character described, work-holding mechanism comprising a shaft mounted to rotate and slide longitudinally and equipped with a head stock, a second shaft slidably mounted parallel with said first mentioned shaft and equipped with a foot-stock, a cross-arm engaging said 20 second shaft and secured against longitudinal movement thereon, said cross-arm rotatably engaging said first mentioned shaft, and means on said first mentioned shaft cooperating with said cross-arm for taking up the thrust between said head stock and foot-stock.

25 19. In a machine of the character described, means for rotating and axially reciprocating the article to be polished, comprising a driven shaft mounted to rotate and slide longitudinally, said shaft being

equipped with a head stock, a second shaft slidably mounted parallel with said first mentioned shaft and equipped with a foot-stock, a cross-arm connecting said shafts 35 and rotatably engaging said first mentioned shaft, means on said two shafts cooperating with said cross-arm for taking up thrust between said head stock and foot-stock, and means connected with said first mentioned 40 shaft for reciprocating said shafts in unison.

20. In a machine of the character described, means for rotating and axially reciprocating the article to be polished comprising a driven shaft mounted to rotate and slide longitudinally, said shaft being equipped with a head stock, a second shaft slidably mounted parallel with said first mentioned shaft and equipped with a foot- 50 stock, a cross-arm connecting said shafts and rotatably engaging said first mentioned shaft, means on said two shafts cooperating with said cross-arm for taking up thrust between said head stock and foot-stock, and means connected with said first mentioned 55 shaft and including reducing gearing mounted on said shafts and a circular cam rotated by said gearing for reciprocating said shafts in unison.

ELMER P. McCLURE.
